R. M. PIERSON

TANK VALVE

Filed Nov. 18, 1926

Inventor
Robert M. Pierson
By Pierson, Cahan & Avery,
Atty's.

UNITED STATES PATENT OFFICE.

ROBERT M. PIERSON, OF AKRON, OHIO, ASSIGNOR TO THE B. F. GOODRICH COMPANY, OF NEW YORK, N. Y., A CORPORATION OF NEW YORK.

TANK VALVE.

Application filed November 18, 1926. Serial No. 149,153.

This invention relates to outlet valves for flush tanks, and its principal object is to provide an improved valve of highly flexible construction, which will effectively seal the outlet and will not lose its shape through long-continued use.

The accompanying drawing is a vertical sectional view showing a preferred form of my invention.

10 In the drawing, 1 is the top or upper portion of the valve which may be of any suitable shape and construction, the form shown being concave, with a central, upwardly-projecting stem 2 in which is embedded the usual 15 metallic spud 3 for connection with the lifting rod, and a stem-base 4 which flares toward the horizontal. I prefer to make this upper portion of vulcanized, soft-rubber compound.

5 is the lower or seating portion, of convex 20 or concoidal form, here shown as approximately hemispherical in outline although its contour might be slightly varied. This portion is also of soft-rubber construction and is integrally joined at its upper end to the outer 25 edge of the top portion 1.

I provide the lower portion with a thickened, annular, reinforcing belt 6 of the same material, which occupies an intermediate zone of said lower portion, substantially co-extensive with the ordinary seating zone of the valve. This thickened zone lies wholly below the junction of the upper and lower portions and is connected with the outer margin of the upper portion 1 by a thinner, 35 annular wall portion 7 lying immediately below said outer margin or line of juncture.

The valve is provided with a relatively wide mouth opening 8, typical of the full-molded type of valve vulcanized between 40 metal surfaces of which the inner one is a core adapted to be withdrawn through the opening 8 after the completed ball has been removed from the outer mold.

In operation, the thickened belt 6 reinforces the valve and prevents permanent distortion thereof at the seating zone, but being of soft-rubber construction, it has the necessary flexibility to effect a proper sealing of the tank outlet. The thinner zone 7 provides a greater radial flexibility in the region immediately below the outer margin of the top portion 1 and allows for a slight spreading tendency of said margin due to the hydrostatic pressure when the tank is full, thus promoting a tight seal. When the valve is unseated by an upward pull thereon, the horizontal, inwardly-acting component of the upward force exerted through the stem-base 4 tends to flex the valve at the thin zone 7 and the upper portion of the thickened zone 60 6, and thus progressively break the seal with a minimum exertion of force.

I claim:

1. A hollow, buoyant tank valve comprising an upper portion, and a soft-rubber lower portion connected to the outer edge of said upper portion, said lower portion being highly flexible and elastic throughout and including a thickened reinforcing belt located in an intermediate zone of said lower portion 65 and lying wholly below its region of greatest diameter at the junction with said upper portion.

2. A hollow, buoyant tank valve comprising a soft-rubber upper portion, and a convex, soft-rubber lower portion integrally joined to said upper portion at the outer edge of the latter, said lower portion having a thickened reinforcing belt located in an intermediate zone thereof and a thinner wall 80 portion above said belt, immediately below the junction of said lower portion with the upper portion.

In witness whereof I have hereunto set my hand this 9th day of November, 1926.

ROBERT M. PIERSON.
